Grindell and Russell, his Atty.

UNITED STATES PATENT OFFICE.

JOHN W. MARK, OF NEW YORK, N. Y.

ILLUMINATING-TILE.

SPECIFICATION forming part of Letters Patent No. 528,004, dated October 23, 1894.

Application filed April 24, 1894. Serial No. 508,879. (No model.)

To all whom it may concern:

Be it known that I, JOHN W. MARK, of New York city, in the county of New York, and in the State of New York, have invented cer-
5 tain new and useful Improvements in Illumi-
nating-Tiles; and I do hereby declare that
the following is a full, clear, and exact de-
scription thereof, reference being had to the
accompanying drawings, in which—

- 10 Figure 1 is a perspective view of my ring
for use in setting illuminating lenses. Fig.
2 is a like view of the same, when combined
with a lens. Fig. 3 is a perspective view of
a tile containing said improvement, and Fig.
15 4 is a vertical section of the same upon a line
passing through the light openings.

Letters of like name and kind refer to like
parts in each of the figures.

The design of my invention is the provision
20 of a lens-inclosing band or ring for illuminat-
ing tiles, that will be cheap of manufac-
ture, and very efficient as a means to securely
hold the lens against accidental displacement,
and to this end said invention consists in the
25 ring or band, and its combination with the
lens and tile, substantially as and for the
purpose hereinafter specified.

My invention relates to that class of illu-
minating tiles in which the lenses are first
30 mounted in a ring or band, and then placed
over the light openings of a tile, and the
spaces around and between them filled with
concrete or like material.

In the carrying of my invention into prac-
35 tice, I construct a ring or band A, of wire
cloth or meshed fabric, and place the same
around a lens B, of such diameter that a space
will be left between them for a filling of ce-
ment C, to unite them. The combined lens
40 and band are then set over one of the light
openings d, formed in a suitable tile body D,
and the spaces around and between are filled
with concrete E, or like material to a level
flush with the surfaces of the lenses.

It will be seen that the cement C and con- 45
crete E will enter and be interlocked in the
interstices of the wire cloth, and thus most
effectually unite the band and lens, and hold
the latter from accidental dislodgement from
its position over the light opening of the tile. 50
Said interstices also enable the absorption
by the concrete E of any excess of moisture
which may tend to collect or pass down around
the lens, and thus, avoid leakage through the
tile as well as to utilize such moisture to save 55
the concrete from disintegration from undue
dryness.

I do not claim as my invention the combi-
nation of a tile body having light openings,
a glass over each of the latter, a ring or band 60
inclosing each glass having openings through
its sides and concrete or the like surround-
ing the ring.

Having thus described my invention, what
I claim is—

1. As an improvement in illuminating tiles,
the combination of a tile body that has a num-
ber of light openings, a lens over each open-
ing, cement around the sides of each lens, a
ring or band formed of wire placed around 70
the cement, and concrete or the like, in the
spaces between the lenses, substantially as
and for the purpose specified.

2. An illuminating tile composed of a tile
body that has a number of light openings, a 75
lens over each opening, a ring or band sur-
rounding the lens, and made of cloth or
meshed fabric, cement between the lens and
band, and concrete in the spaces between the
lenses, substantially as and for the purpose 80
set forth.

In testimony that I claim the foregoing I
have hereunto set my hand this 30th day of
March, 1894.

JOHN W. MARK.
